(57) **CLAIM**

The ornamental design for a crimping tool, as shown and described.

DESCRIPTION

FIG. 1 is a perspective view of the crimping tool of the present invention;

FIG. 2 is a first side view of the crimping tool of the present invention;

FIG. 3 is a second side view, opposite to that of FIG. 2, of the crimping tool of the present invention;

FIG. 4 is a front view of the crimping tool of the present invention;

FIG. 5 is a rear view of the crimping tool of the present invention;

FIG. 6 is a top view of the crimping tool of the present invention; and,

FIG. 7 is a bottom view of the crimping tool of the present invention.

1 Claim, 7 Drawing Sheets
